JOHN GWYNN, OF TIFFIN, OHIO.

Letters Patent No. 90,095, dated May 18, 1869.

HOT-AIR FURNACE.

The Schedule referred to in these Letters Patent and making part of the same.

To all whom it may concern:

Be it known that I, JOHN GWYNN, of Tiffin, in the county of Seneca, and State of Ohio, have invented a new and improved Mode of Constructing "Heaters" for Warming Air for Buildings; and I do hereby declare that the following is a full and exact description thereof, reference being had to the accompanying drawings, and the letters of reference marked thereon.

Figure 1 is a perspective view of the front and right side, with the outer wall removed.

Figure 2 is a front and left side, with outer and part of inner wall removed, showing side of fire-box.

Figure 3 is a view, with the top and radiators removed, showing plan of walls and fire-box.

Figure 4 is the regulator, open and shut.

Figure 5, the castings I I.

Figure 6, the castings J and L.

Figure 7, the castings K and M.

The nature of my invention consists in constructing a "heater," so arranged as to receive plain sheets of iron, for the heat-radiators, which may be readily displaced or replaced, without any disarrangement of the other parts of the heater, thus enabling those who use this invention, to renew the only destructible part, in any season of the year, without further deprivation of its use than for an hour or two.

The peculiar features of this invention may be enumerated thus:

First, the above described.

Second, the sheet-iron radiators form, in connection with the iron and brick-work, two continuous flues, one for fire, the other for air, ascending in alternate thin layers, and traversing each other laterally, or otherwise.

Third, it admits of all the modifications necessary to accommodate all the favorable or unfavorable circumstances of its location; for if the "draught" of the chimney is very inferior, the number of radiators may be reduced to the minimum number. If the draught of chimney be powerful, then the number of radiators may be increased to advantage.

Fourth, the regulator, forming the top of the fire-box, if opened, permits the fire to play directly on the lower radiator, if the heat be insufficient when closed.

Fifth, the shape of the flues insures the spreading out, in thin layers, of both fire and air, thus absorbing and transmitting all the heat the fire is capable of generating.

Sixth, the radiators do not necessarily have to receive the direct action of the fire, which experience shows is better avoided.

To enable others skilled in the art to make and use my invention, I will describe its construction and operation.

The fire-box A, figs. 2 and 3, is of brick, on the sides of which, at the top edge, are several openings, for the heat to pass out into the chamber V, under the lower radiator.

The regulator, fig. 4, is of cast-iron, or other suitable material, operated by moving the rod c c backward and forward, on the same principle as a "Venetian" blind, the frame B being laid on top of the fire-box.

The plate g g g, fig. 2, is a simple plate of cast-iron, inserted in the space between the door-frame and the "grate-bars," on which it lies, to make a close bottom for wood.

The two inner walls, D D, figs. 1, 2, and 3, are of brick, with the openings E E, for the heat to pass into the flues F F.

The outer walls are also of brick, with a suitable space, G G, fig. 3, left between it and the inner wall, of from two to five inches, in which space, by the partition-columns H H, are formed those portions of the air and fire-flues, necessary to alter the directions of the currents.

The inner walls D D are built up three inches higher than the top of the fire-box, and the castings I I laid in mortar thereon, and reach to the outside of the front and rear walls; then two courses of bricks are laid on it, for sixteen inches at each end, on which are placed the castings J and K; then two more courses of brick are laid, as before described, on which are placed the castings L and M, of the same shape as J and K last mentioned, but in reverse positions, from left to right, for the purpose of forming the return-flue for air.

The outer walls are then built up to a sufficient height to form a chamber for the "heated air" above the upper radiator, and allow space for the water-pan N.

The top is then closed over, with brick or iron, or both, leaving suitable outlets for air-pipes on top, to convey the heated air to the registers.

Openings are to be formed in the left-hand outer wall, for the admission of cold air to the radiators, through the space G, the size of which openings will be in proportion to the heater.

The radiators P P P P P are plain sheets of iron, with no other preparation than making the edges parallel, and are slid into the grooves Q Q in the castings I I, J K, L and M.

When so placed, the plates marked R are screwed into their places by the nuts S S.

The flues F F in the rear, co-operate with those in the front, T T, as I will now explain.

When the heat or fire passes into the flues F F, through the openings E E, from the chamber V, it ascends until stopped by the brick wall at U U, when it enters the openings W W in the castings J and K, passing thence to the front, between the second and third radiators.

It leaves them through the front openings X X, and enters the front flues T T, and ascends to the openings Y Y in the castings L and M, and is again turned by the brick wall at U U, and enters between the two upper radiators, and leaves in the rear of the same for the chimney, having thus passed over the whole of the radiating-surface.

Now, the air to be warmed enters at the opening in the outer wall, and then ascending between the outer and inner walls D D, is turned by the flange Z on the casting J, into the opening between the castings I and J, and is thus passed between the first and second radiators; then making its exit on the opposite side, it ascends between the walls until stopped by the flange Z. On the casting L it enters between the third and fourth radiators, making its exit on the opposite side, and ascending into the chamber over the top, or fifth radiator, is ready to be conducted to the registers.

I am aware that the flues formed by the radiators may be connected in front and rear, thus dispensing with the flues F F and T T, but I prefer the mode described.

I am also aware that heaters have been constructed with horizontal and with "return-flues," and I disclaim either of those devices as being part of my invention.

What I claim, and wish to secure by Letters Patent, is—

1. The cast-iron frames I, J, K, L, and M, and the radiators P P, connected, as described, together with the front and rear plates marked R R, and the pecu-

liar form of the brick-work in which they are built, for leading the fire and air in alternating, horizontal, and ascending thin layers, at right angles with each other.

2. The use of a plain sheet of iron, without bend, seam, or rivet, connected to an iron frame by means of grooves, as described, for radiating-surface.

3. The construction of the iron frames I, J, and K, with grooves, intended to receive the edges, and allow the withdrawal and renewal of the radiators P P P, and with orifices to form part of the fire-flues.

4. The forming of a flue, or tube, by the manner described of connecting the sheet-iron to frame, and the manner of making the same flues continuous and ascending, by their relative position with each other, in connection with the brick-work or casting, whichever may be used.

5. The combination of the parts herein described, for the purposes set forth.

JOHN GWYNN.
